OUTPUT MEAN SQUARE SENSING FOR MAGNETIC OUTPUT VOLTAGE REGULATOR

John V. Majercak, Cleveland, Ohio, assignor to Jack & Heintz, Inc., Cleveland, Ohio, a corporation of Delaware

Application September 20, 1955, Serial No. 535,386

6 Claims. (Cl. 323—89)

This invention relates in general to voltage regulators and has for one of its primary objects to provide an improved voltage regulator whose output will be proportional to the root mean square value of the applied voltage, so as to make voltage regulation independent of harmonic content of the applied voltage.

The conventional method of obtaining a signal proportional to the root mean square value of the applied voltage in a voltage regulator is to apply the sensing voltage to the filament of a diode in a direct current bridge circuit in such a manner that a change in the sensing voltage produces an unbalance in the bridge and provides a direct current signal voltage which is applied to the tubes and the tubes, in turn, control the output of a two stage gating magnetic amplifier.

In keeping with the stated primary object of my invention, I propose to provide a voltage regulator consisting of a voltage sensing filament type diode whose output is fed directly into the control coils of a magnetic amplifier that is so constructed as to be a full wave output with windings so arranged that all of the windings are used as control windings during the control half of the cycle and the power windings are used as such during the other half of the cycle. This arrangement makes it possible to use the voltage of the main power transformer as part of the reset voltage using both windings as control windings during the reset half of the cycle reducing control current requirements.

I further propose to employ a duodiode tube and a center tapped filament transformer so constructed and arranged that if one tube filament fails one diode of the tube will be shorted in order to make that half of the circuit inoperative, while the other half of the circuit continues to operate and regulate the voltage.

With the foregoing and other objects in view, the invention resides in the combination of parts and in the details of construction hereinafter set forth in the following specification and appended claims, certain embodiments of which are illustrated in the accompanying drawing, which is a circuit diagram of my improved root mean square sensing magnetic amplifier voltage regulator.

Referring more particularly to the drawing, I have provided a sensing transformer 1, with a primary winding 2 to be connected into the circuit with the alternating current voltage to be controlled and a center-tapped secondary winding 3 for supplying a twin filament 4 of a duodiode, generally indicated at 5. The center tap of the secondary of transformer 1 is connected to the filament 4, at a common point between filament sections 4a, 4b connected across different sections 3a, 3b respectively of the secondary 3 of transformer 1. The filament sections 4a, 4b cooperate in the manner of a diode with plates 6, 7 respectively.

The remainder of the circuit includes a power and plate transformer 8 with a primary winding 9. It also includes diode plate 6 of diode 5 in series with a secondary winding 10 of the power and plate transformer 8

2

and the secondary, or control, winding 11 of a magnetic amplifier 12, the primary, or control and power winding 13, of which is in series with a section 14a of a center-tapped secondary winding 14 of transformer 8. Likewise, diode plate 7 and filament section 4b of diode 5 are in series with a secondary winding 15 of transformer 8 and with a control, or secondary, winding 16, of a magnetic amplifier 17, the primary, or control and power winding 18, of which is in series with a section 14b of secondary winding 14 of transformer 8.

The output terminals of the regulator are designated by the reference character 19a, 19b. The terminal 19a is connected to the mid-point of secondary coil 14 and the terminal 19b is connected to the connection between the winding 13 and the winding 11 of magnetic amplifier 12 through a self-saturating rectifier 20 and to the connection between the windings 16 and 18 of magnetic amplifier 17 through a self-saturating rectifier 21. The rectifier 20 permits current to flow from the center tap on the secondary coil 14 through the winding 13 when the center tap is positive with respect to the other end of section 14a of the secondary coil 14 and the rectifier 21 permits current to flow from the center tap through the winding 18 of magnetic amplifier 17 when the center tap of secondary coil 14 is positive with respect to the other end of section 14b of coil 14. It can thus be seen that when output current is flowing through winding 13 of amplifier 12, the polarity of secondary section 13b will be such that no output current flows through winding 18 of amplifier 17 and vice versa. The output terminals 19a, 19b are connected to the load and current controlled in accordance with the input voltage to sensing transformer 1 is supplied to the load which may be the field winding of an alternator.

The amplifiers 12, 17 may be termed gating magnetic amplifiers which are connected in push-pull relationship. Each gating magnetic amplifier has a control or reset cycle under the control of diode 5 followed by a firing or conduction cycle where output current from secondary coil 13 flows in the power winding. At any given half cycle of applied voltage one gating magnetic amplifier will be resetting while the other will be conducting.

On the half cycle, when the polarities of the power and plate transformer 8 are such that the center tap of secondary coil 14 is positive with respect to the other end of section 14b, output current will flow in a circuit containing winding 19 of transformer 8, the control and power winding 18 of gating magnetic amplifier 17, rectifier 21, and the output. The control and power winding 18 of the gating magnetic amplifier 17 will have a high impedance at the beginning part of the half cycles where output current is flowing and then will saturate due to the magnetizing effect of the output current and allow maximum current to flow for the remainder of that same half cycle through the load.

The level of magnetization at the beginning of the half cycle determines the amount of current flowing through the load during the half cycle by determining the time in the cycle necessary to saturate the core of the magnetic amplifier. During the same half cycle that output current is flowing in magnetic amplifier 17, the core of the gating magnetic amplifier 12 is being reset to a predetermined level of magnetization as determined by transformer 1 since the polarity of secondary coil 10 is such that the plate 6 is positive with respect to filament 4 and reset current will flow through the following circuit: from secondary coil 15 through plate 7 of diode 5, through filament section 4a to the center tap of power and plate transformer 8, through winding 14a of the same transformer, through control and power winding 13, control winding 11, and back to power and plate transformer winding 10. The

amount of current flowing through this circuit will depend upon the emission of the filament section 4a of diode 5, which in turn is dependent upon the applied filament voltage. Therefore, the reset, or level of magnetization at the beginning of the output half cycle of the gating magnetic amplifier 12, is controlled by the amount of emission of the filament section 4a of diode 5. A rheostat 23 may be connected in series with the primary 2 of transformer 1 to adjust the output voltage to suit the particular conditions. On the next half cycle the reset and conduction cycles interchange between the gating magnetic amplifiers due to the change in polarities of the secondary coils 10, 14 and 15. It will be noted that current cannot flow in the control windings of 11, 16 of the amplifiers 12, 17 on the respective half cycles when output current is flowing in the control and power windings 13, 18 respectively since the polarities of secondary coils 10, 15 respectively are such that the plate of diode connected in the respective reset circuit is negative with respect to the corresponding filament section. The rectifiers 20, 21 prevent current from the secondary coil 14 from flowing in windings 13, 18 respectively when the amplifiers 12, 17 respectively are being reset. Thus, every half cycle one magnetic amplifier is conducting through the load while the other is resetting.

A rectifier 24 connected across the output is used as an inductance isolating rectifier when the output of the regulator supplies power to inductive load such as an alternator control field winding. This rectifier permits current flow through the output and through rectifier 24 due to stored energy of the inductive load.

The inner ends of each of the filament sections 4a, 4b are connected to a fixed support 24 in the tube of the duodiode 5 by resilient arms 25, 26 respectively, which are fixed at one of their ends to the support 24 and at their outer ends to the inner end of their respective filament sections. The bias of the arms 25, 26 is such that if the filament sections 4a, 4b break, the arms connected thereto will move into engagement with members 27, 28 respectively, connected to the plates 6, 7 respectively, to form a short circuit from the support 24 to the plates. If only one filament section breaks, only the arm connected thereto will cause a short circuit between the support 24 and the corresponding member 27 or 28.

The connection between the center tap of secondary coil 14 and the filament 4 is made at the point 24 and when either of the arms 25, 26 contacts its corresponding member 27 or 28 a short circuit is completed which will allow sufficient control current to flow in the reset or control cycle that on the half cycle, which is normally the reset or control cycle the level of magnetization is reduced to a point where substantially no current will flow on the output cycle. The other half of the duodiode and the other amplifier will continue functioning in the normal manner unless the corresponding filament section also breaks.

As stated before, the primary object is to provide a voltage regulator whose output is proportional to the root mean square value of the applied voltage, thus making voltage regulation independent of harmonic content of the applied voltage. By means of my improved voltage regulator, the output of the voltage sensing filament type diode 5 is fed directly into the control coils 10 and 16 of the magnetic amplifiers 11 and 17. The magnetic amplifier is a full wave output with windings so arranged that all of the windings 10, 12, 16 and 18 are used as control windings during their respective control half of the cycle and the power windings 12 and 18 are used as such during their respective output half of the cycle. Using both sets of windings as control windings during the reset half of the cycle reduces control current requirements.

In view of the fact that the sensing tube 5 has its filament 4 center tapped at 23, if one section of the filament fails, one diode of the tube will be shorted, due to the internal construction of the tube, so as to make that half

of the circuit inoperative, while the other section will continue to operate and regulate.

While I have referred to rectifiers 20 and 21 as being self-saturating it is to be understood that I may also employ rectifiers that are not self-saturating.

What I claim is:

1. In a root mean square sensing magnetic amplifier output voltage regulator, a twin voltage sensing filament type diode, a sensing transformer for supplying the filament of said twin diode, a power and plate transformer, a plurality of magnetic amplifiers each having a control winding and a control and power winding, each of said diodes being in series with said power and plate transformer and with the control winding of its respective magnetic amplifier, said twin diode being provided with a center tapped filament having respective sections in series with the control windings of said magnetic amplifiers.

2. In a root mean square sensing magnetic amplifier output voltage regulator, a voltage sensing filament type twin diode, a sensing transformer for supplying the filament of said twin diode, a power and plate transformer, a first and second magnetic amplifier each having a control winding and a control and power winding, each one of said diodes being in series with a different secondary winding of said power and plate transformer and with the control winding of a different one of said magnetic amplifiers.

3. In a voltage regulator, first and second magnetic amplifiers connected in push-pull relationship, each of said amplifiers having output windings and control winding, first and second control circuits for controlling the current in the control winding of said first and second magnetic amplifiers respectively, each of said circuits including a diode having a filament and a plate, means controlling the emission of said filaments in accordance with a voltage condition to thereby determine the current conducted by the diodes, each of said diodes including means for establishing a circuit therethrough upon failure of its filament to maintain a complete control circuit for the respective control winding.

4. In a voltage regulator, first and second magnetic amplifiers connected in push-pull relationship, each of said amplifiers having output windings and control winding, first and second control circuits for controlling the current in the control winding of said first and second magnetic amplifiers respectively, each of said circuits including a diode having a filament and a plate, a transformer having a center tapped secondary with the first and second sections thereof connected in series with the filaments of said first and second diodes respectively for controlling the emission of said filaments in accordance with a voltage condition to thereby determine the current conducted by the diodes, each of said diodes including means for establishing a circuit therethrough upon failure of its filament to maintain a complete control circuit for the respective control winding, each of said control circuits reducing the output of its corresponding magnetic amplifier substantially to zero upon the breaking of the filament in its corresponding diode.

5. In a voltage regulator, first and second magnetic amplifiers connected in push-pull relationship, each of said amplifiers having output windings and control winding, first and second control circuits for controlling the current in the control winding of said first and second magnetic amplifiers respectively, each of said circuits including a diode having a filament and a plate, a transformer having a center tapped secondary with the first and second sections thereof connected in series with the filaments of said first and second diodes respectively for controlling the emission of said filaments in accordance with a voltage condition to thereby determine the current conducted by the diodes, each of said diodes including means for establishing a circuit therethrough upon failure of its filament to maintain a complete control circuit for the respective control winding, each of said con-

trol circuits reducing the output of its corresponding magnetic amplifier substantially to zero upon the breaking of the filament in its corresponding diode, said diodes being provided by a single duodiode having twin filaments and plates and the primary of said transformer being connected into a circuit having a voltage condition to be controlled and the output of said amplifiers being utilized to control said voltage condition.

6. In a voltage regulator, a voltage twin filament type diode, having first and second plates and first and second filaments providing two diodes, a sensing transformer for supplying power to said filaments, a power and plate transformer having a plurality of secondary windings, first and second magnetic amplifiers each having a control winding and an output winding, said diodes being

connected respectively in series with a secondary winding of said power and plate transformer and with the control windings of said first and second magnetic amplifiers, each of said diodes having means for providing a short circuit connection through the diode to maintain said series circuits complete on a breakdown of a filament.
